STATUETTE

James Robert Black, Jr., Ann Arbor, Mich., assignor to People Products, Troy, Mich.

Filed Jan. 13, 1971, Ser. No. 106,321

Term of patent 14 years

Int. Cl. D11—02

U.S. Cl. D29—24

FIG. 1 is a front elevational view of a statuette showing my new design;

FIG. 2 is a side elevational view taken from the left of FIG. 1;

FIG. 3 is a side elevational view taken from the right of FIG. 1; and

FIG. 4 is a top plan view thereof.

I claim:

The ornamental design for a statuette, as shown and described.

No references cited.
